UNITED STATES PATENT OFFICE

2,001,880

ADVERTISING DEVICE

Herbert D. Lambourne, Baltimore, Md., assignor of forty-five per cent to John G. Onnen, twenty per cent to John W. Simpson, ten per cent to Stanley E. Simpson, and five per cent to George H. Becker, all of Baltimore, Md.

Application June 19, 1934, Serial No. 731,272

3 Claims. (Cl. 40—138)

This invention refers to advertising devices and more particularly to those adapted for use in public vehicles, and has for its objects to provide a mechanism in the devices that will enable them to produce horizontal, vertical and cross-wise movements. Another object is to have the device noiseless and capable of giving active movements instead of a slow and monotonous nature. A further object is to provide several types of movements in the same device. Other objects will become apparent as the invention is more fully set forth.

The invention consists in the details of construction and in the combination and arrangement of the several parts, whereby advantages are attained which will be hereinafter more fully indicated.

In the drawing which is provided to make the invention more clearly understood:

20 Figure 1 shows an advertising device as seen from its front view.

Figure 2 is a detail view of the interior mechanism showing the operative parts having a vertical, horizontal, and sidewise or cross-wise movement.

25 Figure 3 is a sectional view through Figure 1 on line 3—3.

Similar reference characters refer to similar parts throughout the drawing.

30 In the construction indicated in the drawing I represents a card or background on which an advertising outline is provided. A man's face 2 is indicated with the eyes 3 moveable in a vertical and side-wise or horizontal direction. The lower lip, or chin, 4 is also moveable up and down or in a vertical direction, and when it does so, shows more or less of the bottom teeth. A hand 5 moves horizontally and has a tooth brush 6 that moves with it. At the lower portion of the background is provided a tooth-paste tube 7 with its cap 8 located immovably, while the rest of the tube can move back and forth at an angle, showing tooth cream between the top of the tube and its cap as it does so.

45 The eyes consist of round discs 9 of any suitable material supported on delicate springs 10 above, attached to pins 11 on the frame of the background. The discs 9 have wire rods 12 connected below and slightly weighted at 13, while a cross-brace 14 connects them so they will be the same distance apart. Rubber stops 15 limit the upward and downward movement of the cross-brace, while the rubber stops 15 limit the side-wise or horizontal movement. The moveable lip or chin 4 is attached to a delicate spring 16 and

rod 17 which runs in a guide staple 18 and has a weight 19 for keeping the spring in tension, on the pin 30.

The hand 5 is attached to a pendulum rod 20 secured to pin 21 at the point 22 and weight 31. The pendulum swings and is limited in its travel by the slot 23 in the background. This swing gives the hand a back and forth movement and makes the brush move over the teeth.

The tube 7 is attached to a rod 24 at 25 and is kept delicately tensioned by springs 26 secured at 27. As the tube moves, it moves away from the cap and afterwards towards it. Strings 40 tie the various mechanisms together.

The operation of the whole device is as follows. The vehicle in which the device is used, is jolted in its transportation and gives the advertising device shakes from time to time. These shakings 15 jolt the weights connected with the eyes and cause the springs to act, making the eyes move up and 20 down and side-wise. The rubber stops limiting the movement and giving an action of their own in a noiseless manner.

At the same time, the lip or chin 4 moves up and 25 down and the hand and brush move with a horizontal swing. The tube also moves in an angular direction from the cap and this gives an animated movement which the observer is compelled to watch.

It is readily appreciated that the device is very 30 interesting from an advertising point of view, and is comparatively simple, and is characteristic in that the motions are not definitely controlled but may follow a varied system of actions due to the independence of the parts and the different manner of motivating them.

While but one form of the invention is shown in the drawing, it is not desired to limit this application for patent to this particular construction or in any other way otherwise than limited 40 by the prior art, as it is known that other constructions could be used using the same principles and coming within the scope of the appended claims.

I claim:

1. In a device of the class described, comprising a background panel with a face painted thereon having openings at the positions of the eyes, eye discs representing eye balls and pupils resiliently mounted on the background card behind said 50 openings, with guides to permit a movement up-and-down thereof and a relatively slight horizontal movement, a member representing a hand mounted on the front side of the panel and adapted to have a horizontal movement, a pendulum 55

link to so operate the hand, a member representing the lower lips and jaw of the face mounted on the front of the panel, a link for resiliently suspending the last mentioned member and having a weight attached thereto all adapted to give vertical movements to the same, a member representing a product mounted on the front of the panel in a slanting direction and having resilient attachments thereto, and a plurality of links interconnected with said discs, hand member, jaw member and product members to make them actuate with each other.

2. In a device of the class described comprising a background panel having a face painted thereon having openings at the positions of the eyes, the lower jaw, and at other places thereon, eye discs representing eye pupils resiliently mounted on said panel behind said openings and having links connected therewith to restrict the movement thereof, a member representing a hand mounted on the front of the panel and attached to a weighted pendulum link secured behind the hand and panel and having a horizontal swing, a member representing the lower jaw of a face mounted on the front of the panel at the position of the jaw of painted face, a resilient link mechanism supporting said lower jaw member and mounted behind the said panel and adapted to give the member a restricted vertical movement, a member painted to represent a commercial article mounted on the front of the panel in a slanting direction, springs and rod members on the back of

the panel and attached through one of said openings to the said commercial article member and adapted to give the same a restricted slanting directional movement, and a plurality of strings for tying the said links together.

3. In a device of the class described having a panel with a face painted thereon with openings at the position of the eyes, the combination of discs with eye balls painted thereon mounted in back of said openings, a plurality of springs attached to the discs for resiliently actuating and supporting the same, weighted links cross connected attached to the discs and adapted to give them erratic vertical and horizontal movements, a member representing a hand and tooth brush mounted on the front of the panel with the brush in line with the mouth of the said face and adapted to move to-and-fro, links mounted on the back of the panel having a pendulum and weight and a connection extending through the panel to support and move the hand member aforementioned, a member representing a jaw for said face and positioned to coact with the representation of the face on the panel, links, weight, spring and guide staples for actuating the jaw member and mounted on the back of the panel, a member representing a commercial article mounted on the panel and resiliently attached thereto, and a plurality of strings for tying the said links and actuating the various members.

HERBERT D. LAMBOURNE.
